(57) **CLAIM**

The ornamental design for a baby wrap, as shown and described.

DESCRIPTION

FIG. 1 is a front view of a baby wrap showing our new design;
FIG. 2 is a back view thereof;

FIG. 3 is a reference showing the baby wrap in the position of use;

FIG. 4 is a reference showing the baby wrap in the position of use;

FIG. 5 is a reference showing the baby wrap in the position of use;

FIG. 6 is a front view with the showing of close-up view thereof; and,

FIG. 7 is a reference showing the baby wrap in the position of use.

The broken lines shown illustrate portions of the baby wrap that form no part of the claimed design.

1 Claim, 7 Drawing Sheets
